COMBINED PORTABLE BAR AND SODA FOUNTAIN

Frank A. Turiace, Jr., 2820 N. Main St.,
Los Angeles, Calif.

Filed Feb. 7, 1966, Ser. No. 948

Term of patent 14 years

(Cl. D2—3)

Fig. 1.

Fig. 2.

FIG. 1 is a perspective view, as seen from the front of a combined portable bar and soda fountain, showing my new design.

FIG. 2 is a perspective view thereof, as seen from the rear.

The dominant features of the design are shown in the drawing in full lines.

I claim:

The ornamental design for a combined portable bar and soda fountain, substantially as shown and described.
